US0D1028374S

(12) **United States Design Patent** (10) **Patent No.:** **US D1,028,374 S**
(45) **Date of Patent:** **** May 21, 2024**

(54) **FIRE EXTINGUISHER**

(71) Applicant: **Chengcheng Huang**, Hunan (CN)

(72) Inventor: **Chengcheng Huang**, Hunan (CN)

(**) Term: **15 Years**

(21) Appl. No.: **29/880,079**

(22) Filed: **Jul. 17, 2023**

(51) LOC (14) Cl. **29-01**

(52) U.S. Cl.

USPC **D29/125**

(58) **Field of Classification Search**

(57) **CLAIM**

The ornamental design for a fire extinguisher, as shown and described.

DESCRIPTION

FIG. 1 is a top, front, right side perspective view of a fire extinguisher, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom, rear, left side perspective view thereof.

The broken lines illustrate portions of the article that form no part of the claimed design.

1 Claim, 8 Drawing Sheets
